United States Patent Office.

F. M. RANONS, OF LITTLE SHASTA VALLEY, CALIFORNIA.

Letters Patent No. 96,147, dated October 26, 1869.

IMPROVEMENT IN GATE-LATCHES.

The Schedule referred to in these Letters Patent and making part of the same.

To all whom it may concern:

Be it known that I, F. M. RANONS, of Little Shasta Valley, in the county of Shasta, and State of California, have invented a new and improved Gate-Latch; and I do hereby declare that the following is a full, clear, and exact description thereof, which will enable others skilled in the art to make and use the same, reference being had to the accompanying drawing, forming part of this specification.

The object of this invention is to provide a cheap and simple gate-latch, calculated to be better adapted for securely fastening gates than any now in use, and less liable to be disarranged by the settling of the gates.

It consists in a sliding latch, having a hooked end, and a spiral spring, arranged to constantly draw the latch into the case, which is fixed on the gate, in connection with a double-bevelled catch, which draws the latch lengthwise, and at the same time raises it when the gate shuts, and behind which the hooked end of the latch is drawn back into a notch by the spring, being forced down by a longitudinal spring, the said notch holding the gate closed, and preventing the latch from being lifted up by animals, all as herein-after more fully specified.

Figure 1 represents a front elevation of my improved gate-fastening, with the side of the case removed.

Figure 2 represents a top view of the same.

Similar letters of reference indicate corresponding parts.

A represents a sliding latch, arranged in a case, B, to be fastened to the gate.

The outer end of the latch is provided with a hooked point, bent downward and backward, as represented at C, in dotted lines. The rear end is connected to the case by a coiled spring, D, having a constant tendency to draw it back, and a longitudinal spring to force the latch down, when lifted in latching.

E represents a double-bevelled catch, to be fastened to the post, and having a notch behind the vertical face, into which the hooked point C is drawn by the spring, when the gate closes. This notch prevents the bolt from being raised up.

The case of the bolt is made wider than the bolt, to afford room for the latch to be raised to the top of the horizontal face of the catch when the gate sags, the horizontal face of said catch being bevelled, to allow the latch to slide into place without difficulty.

F represents a thumb-piece, for sliding the bolt for unfastening the gate.

G represents the longitudinal spring placed in the case, and resting on the upper side of the latch, to hold and force it to its place in the catch.

Having thus described my invention,

What I claim as new, and desire to secure by Letters Patent, is—

The catch E, constructed as described, in combination with the hooked slide-latch A, and springs D and G, all arranged and operating substantially as herein shown and described, for the purpose specified.

F. M. RANONS.
